TRACK BUFFER.

No. 380,680.

Patented Apr. 10, 1888.

UNITED STATES PATENT OFFICE.

ROBERT P. GARSED, OF NORRISTOWN, PENNSYLVANIA.

TRACK-BUFFER.

SPECIFICATION forming part of Letters Patent No. 380,680, dated April 10, 1888.

Application filed December 10, 1887. Serial No. 257,553. (No model.)

To all whom it may concern:

Be it known that I, ROBERT P. GARSED, a citizen of the United States, and a resident of Norristown, Montgomery county, and State of Pennsylvania, have invented a new and useful Improvement in Track-Buffers, of which the following is a specification.

The object of my invention is to furnish a new and improved track-buffer for operation at the terminals of railways in arresting motion of a moving train when said train would move in advance of the point desired; and it relates more particularly to mechanism by which the device is restored to its starting-point, the major part of the device being already patented to me by patents numbered 308,096, 318,462, 318,463, 330,009, and 341,568.

In the accompanying drawings, forming part of this specification, and in which similar letters of reference indicate like parts throughout the several views, Figure 1 is a side view of the device upon a railroad-track. Fig. 2 is a top view of one of the housings. Fig. 3 is a front view of the device without the housings; Fig. 4, a top view without the weight and its supporting mechanism being shown, and also without other parts of the device being shown; Fig. 5, a side view of the under friction-bar with chain fastened to rod of the spring-chambers, which serves as a medium by which the apparatus is restored to its first position; Fig. 6, a bottom view of the weight with spring-pockets and supporting-rod openings shown; Fig. 7, a top view of the same; Fig. 8, a side view of a flanged rod which passes upward through the weight and holds the spring, through the center of which it also passes, in position; Fig. 9, a side view of a shackle which screws on top of the flanged rod, and, through the medium of a coupling-bar, is attached to the weight-chains; Fig. 10, a bottom view of the same; Fig. 11, a side view of a spiral spring which goes in the pockets of the weight, also in the chambers of the supporting-rods, the chambers of the gaging-beam, and the chambers of the anchoring-bar, as well as in the spring chambers of the housings, and, finally, it serves, by surrounding the supporting-rods at their base, as a medium to soften the force of concussion, as will be hereinafter explained. Fig. 12 is a top view of the coupling-bar, which is made in

two pieces of half-round iron, and passes, when in position, through the end links of the weight-chains and then through the shackles, and thus supports the weight by a less number of chains than there are spring-rods, the openings in this coupling-bar serving to surround the inner supporting-rods which pass upward through the center of the weight. Fig. 13 is a side view of this coupling-bar; Fig. 14, an end view of the same; Fig. 15, a side view of a spring-chamber which screws into the rear of the gaging-beam, as well as into a cap screwed into the anchoring-bar, and by the slot shown in it allows the rod which is surrounded by the weight-chain to work back and forth; Fig. 16, a top view of the same. Fig. 17 is an outside view of a metal cap which serves to hold the spring-chambers to the anchoring-bar, and also to keep the weight-supporting rods together at their upper ends, these ends having the chain-rod slots cut to their outer edges. Fig. 18 is a section of Fig. 17, showing the threaded inside. Fig. 19 is a top view of the weight-plate which supports the bottom of the weight at times upon the springs on the gaging-beam. Fig. 20 is a top or side view of the flanged chain-rod, between the flanges of which the upper ends of the outer supporting-rods go and are kept in position. The intermediate part of this rod passes in the openings of the inner supporting-rods, and, bearing upon the tops of the inclosed springs, supports the weight-chains which surround it, as shown. Fig. 21 is a side view of the tops of the outer supporting-rods and the spring-chambers of the inner supporting-rods. Fig. 22 is a top view of Fig. 21. Fig. 23 is a side view of a gib whose upturned end is inserted in an opening in the rear of the housings, and is thus held in place. It receives the bearing of the car-wheels upon the rails. Fig. 24 is a top view of Fig. 23. Fig. 25 is a side view of a chain-rod, and Fig. 26 an end view. Fig. 27 shows a front view of the bearing-bar for the springs in the pockets of the gaging-beam H, and Fig. 28 an end view of the same. Fig. 29 is a side view of the inclined-faced bed-bars upon which the upper friction-bar slides, and through the largest circular opening of which the ends of bearing-bar A' pass to bear upon the gaging-beam springs in different parts of said beam. Fig.

30 is an end of the same. Fig. 31 is a front view of part of the housing-faces, and Fig. 32 is an end view of the spiral springs which go in the pockets of the housings. Fig. 33 is an end view of Fig. 20. Fig. 34 is an end view of the weight-plate s.

A represents either rail of a railroad; B, a metal housing with an upper and lower face with laterally-projecting sides, and a longitudinally-projecting end adapted to slide thereon. Care inclined-faced bars situated between the tracks A and running parallel with them.

D is an under friction-bar with hooks D', to which the weight-chains E are attached at their one end.

F is the chain-rod which receives the bearing of the chain E at the anchoring-bar G and at the gaging-beam H of the device.

I is a spring-chamber which holds a spiral spring, J.

K are the outer weight-supporting rods, and L are the inner weight-supporting rods.

M are metal caps whose functions are before mentioned.

N is the weight which is used to restore the housings B to their first position. O is a flanged spring-rod, and P the shackle thereof.

R is the coupling-bar for chains F and shackles P.

S is the weight-plate, which allows the supporting-rods to pass through it when in position.

T is the flanged chain rod or shaft which serves both to allow the chains E to pass over and bear upon it and to keep the outer supporting-rods in position.

U are the gibbs which are fastened to the rear of the housings and extend along the top of the rails. The lugs U' upon them serve to keep them in position, and the lugs nearest the housings bear on both sides of the projecting ends of said housings in keeping them down, and thus have an advantage over the flanges of the car-wheels, which would only bear on one side of these ends.

J' are spring-pockets to receive the springs J in the different parts of the device. K' are pins riveted through the hollow outer supporting-bars K at a distance from their top to allow the spiral springs J to rest.

C' represents an opening in the ends of bed-bars C to allow the ends of a cross bearing-bar, A', to pass, which holds the springs J in place in the pockets of the gaging-beam H. The ends of this bearing-bar where they bear against the springs are flat, and at their rear face are round to suit the shape of the openings in the bed-bars C, through which they pass. When the forward ends of the housings are far enough advanced to press against the springs of the gaging-beam, this cross bearing-bar receives such pressure and moves back and forth with said springs, and by abutting against the edges of the openings C' of the bed-bars C keep these spiral springs from getting out of their pockets. Figs. 27 and 28

show a front view and end view of this bar, respectively.

B' represents a metal plate supported in position in front of the impact-springs of the housings by rods a a, which pass through openings in the projecting sides of B of the housings, and with the springs work back and forth, the rods with nuts on their ends not allowing the springs to get out of place. There are two under friction-bars, D, which may be connected in any suitable way. A side view of the bed-bars C is shown in Fig. 29 to better advantage. Fig. 30 shows an end view.

The operation of the upper friction-bar (marked Z) is that it rises with the advance of the housings and falls with their retreat. During their advance the upper faces of its ends bear upon the upper part of the openings in the housings through which it passes, and its intermediate parts upon the bed-bars C, and thus produces friction. It is a hollow rectangular-shaped piece of metal, and is at the lower end of the openings in the housings when said housings are at their starting-point, and at the upper end of these openings when the housings are at the end of their throw, explained in my other patents. The spiral springs surrounding iron rods passing lengthwise through the inclined slot in the housings, in which said bar Z rises and falls with the advance and retreat of the housings, serve to retard the advance of the device as well as to cushion it.

The operation of the device is as follows: A train of cars moves upon the rails A in the direction of the arrows, Fig. 1, and the end trucks of the first car run first upon the gibbs U, and then, abutting against the lower row of pocketed springs upon the housings, are prevented from revolving. Simultaneously with the abutting of the trucks the platform of the car strikes against the upper row of pocketed springs on each housing, and thus the body of the car cannot shoot forward when the trucks are held back, (and whether the trucks first abut or not, they will not revolve upon the gibbs should the platform first abut.) Immediately thereafter, if the blow be hard enough, the housings advance upon the rails and, producing friction, absorb the blow of the cars in a short distance without jarring. As the housings advance, the weight N is raised, through the medium of the chains E, being fastened to them at their one end and to the rear side of the rear friction-bar at their other end. These under friction-bars at their projecting ends keep the housings from rising from the tracks, and being placed between projecting spiral springs carried in the housings, these rear springs receive the first pressure upon the advance of the housings, and then the rear spring-rod, F, Figs. 4 and 5, is borne upon, and in turn the row of springs J in the chambers, screwed by the caps M into lugs on the anchoring-bar G, Fig. 4. This anchoring-bar is held in place by passing within openings C", of suitable shape, in the rear of the bed-bars C, or by being screwed fast to the ties of

the road. The frontspring-rod, F, is next borne upon, and so the other row of springs in these forward chambers, which, with or without the caps M, may be screwed into the rear face of 5 the gaging-beam H. Next the chains go over the flanged rod T, which, if desirable, may have a sleeve over the parts where the chains bear to ease the chain in its movements, and then in turn the upper springs in the rods K 10 and L receive the shock; and, lastly, the springs within the pockets of the weight receive the pressure of the flange of the rod O, and thus jarring is overcome in raising the weight N suddenly. This end is attained, also, and in a great 15 measure, by the lower springs surrounding the supporting-rods, as it will be seen that when the jerk of the chains E is very sudden the collapsing of the pocketed springs before mentioned is such that the weight immediately 20 drops instead of rising, and before a second jerk is given to the chains, incident to this sudden dropping, these lower springs catch the weight and assist in rebounding it as the chains again are hauled taut by the rapid 25 advance of the housings.

The plate S rests upon these last-mentioned springs, and has a small space between it and the bottom of the weight N when the device is at rest at its starting-point. The supporting- 30 rods K and L pass through the openings in this plate before being screwed into openings in the top of gaging-beam H. They are made of ordinary wrought-iron pipe. More than one plate S may be used to regulate the distance 35 between the bottom of weight N and the surrounding springs, which latter will also receive the shock from the weight in case the chains should break. When the cars retreat, the weight N by gravity causes the housings to 40 return to their starting-point. The gibs U, by receiving the weight of the car, tend to keep the housings down at this end, as the blow of the platform tends to tilt them. Their thickness is made such as to raise the cars 45 a desired height to allow the first brake-beam to pass over the inclined bed-bars to a desired distance for the housings to advance, and besides being an element in stopping the cars, they are of further use in giving a dis- 50 tance for the drillers of trains to keep off, as it is preferable that they only be struck (the housings) by accident, as when the cars would run, by miscalculations in drilling or by slipping of brakes, beyond the end of 55 tracks. The flanged rod O, Fig. 8, has a hole in its threaded end for insertion of a spud to tighten or loosen it when in place, that the weight may be lifted evenly by these rods.

The further advantages of the coupling-bar 60 R are that, it being in halves, it can be put in and out of place without taking out the other parts, and it unites all the shackles of the flanged spring-rods with even pressure at one time, and does away with a chain-hook to each 65 shackle, and thus permits any number of springs (that each need a flanged rod and shackle) to be used without as many chains

and hooks. After it is put in halves through the shackles and the end links of the chain, it is by the latter held in position, and its up- 70 turned ends serve to keep the end shackles from slipping off.

The advantages of the spring-supporting bars passing through the weight will be understood, as the weight in moving up and 75 down would get out of position without them. The outside ones, which are of larger diameter than the inner ones, extend within the grooves on each side of the weight, as shown. The rows of pocketed springs, against which the 80 train first strikes, also serve to cushion the blow to the weight, as well as absorbing the shock to the device upon its being struck suddenly, and their being placed vertically in rows of pockets a desired and great number of them 85 can be used by simply adding height to the tapering sides of the housings, whereas if they were in pockets placed crosswise a complicated and costly construction of the device would be necessary. The fender-plates B', 90 which bear against these springs, being struck near their vertical centers, their strength is made such as to compress powerful springs at some distance from such centers. The rods a, 95 instead of passing through the projecting sides B of the housings, may pass centrally through the springs and through an opening to a desired distance within the sides of the housings. Finally, should the apparatus ever be struck hard enough to send it to the end of its throw, 100 the pocketed springs in the gaging-beam H receive the final pressure.

The operation of the device when struck by a train of cars can be better understood by knowing that instead of one even and continuous push there is generally a series of 105 easy jolts from said cars to the device.

One great advantage of the chain-springs being pocketed with chain-rods to receive the pressure of the chain is that as many springs 110 as are necessary can be used, as well as that by this means we compress said springs instead of distending them, to obviate jarring to a pulling chain, and again by the means shown there is no liability of breakage, and, finally, 115 a necessary element is supplied in a simple and cheap way in lifting a weight rapidly. The bed-bars C keep the two lower chain-rods from moving endwise out of place.

Finally, the effectiveness of this track-buffer 120 may be easily calculated, (without including the full resisting-power of the springs surrounding the tension-rods within the slots of the housings)—as, for instance, the blow of a 125 train of six cars and a locomotive running at a speed of ten miles an hour, (which speed they scarcely ever reach in a depot,) the cars weighing eighteen tons each and the locomotive sixty tons, we have a blow of one hundred and twenty-three thousand pounds. Now 130 there are eight pocketed springs on each upper face of the housings where the platforms strike, and four such springs on each lower face where the wheels strike, each spring when

fully compressed resisting four thousand seven hundred pounds, (there being three in each pocket, the smaller within the larger,) making a total of twenty-four springs, equaling one hundred and twelve thousand eight hundred pounds resistance at these points. After the housings advance somewhat the resisting force of the springs surrounding the tension-rods in the inclined slots of the housings, which springs bear against the upper face of and retard the advance of the upper friction-bar, and thus retarding the device, are brought into play at a pressure each of five thousand pounds, making ten thousand pounds more resistance from these parts. Near the end of this pressure the front face of the forward under friction-bar abuts against the rear part of the webs of the front feet of the bed-bars C and the rear pocketed springs in the sides of the housings, against which these under friction-bars bear. Both under friction-bars, receiving this pressure when joined together, are in turn effectual, and give a combined resistance of twenty-four thousand pounds, and during this latter resistance the pocketed springs in the gaging-beam pressed against by the front faces of each housing are brought into play with a force when fully collapsed of thirty-four thousand pounds, and thus we have a resisting force in these springs alone of over one hundred and eighty thousand pounds, without counting the resisting force of the friction produced by the various elements of the device as it advances upon the rails and bed-bars. This friction being many times more effective than the resisting force of the springs, which latter, as will be seen, may be increased, if desired, and as the trains, as before stated, advance by a series of easy jolts, the springs re-cover themselves a number of times, and as at each collapsing the force of the blow is being absorbed it is almost impossible that the device will ever reach the end of its throw by any blow given by accident in a depot. The ends of the anchoring-bar G, for better security, pass also through the webs of the rails A.

Some of the elements may be abandoned and the device as a buffer operated without them. For instance, the upper friction-bar may be dispensed with, and consequently the tension-rods in the inclined slots of the housings, though the device then would not be so effectual; also, if weight N be used in a pit, rods K and L may be left out.

The plates E' may be made to suit the shape of the brake-beams and platforms of the cars which strike them, and the end tracks, A, of the road may, if convenient, be put at an incline, as less weight will then be required to return the buffer to its first position.

Having thus described my invention, what I claim as new, and desire to secure by Letters Patent, is—

1. In combination, the tracks A, the housings B, and the attached weight N, said housings adapted to advance and retreat, and the weight N having spring-pockets and support-

ing-rod openings, the supporting-rods K and L, with connecting chain-rod T, and the springs J and the chains E, with shackles P and flanged 70 spring-rod O, substantially as and for the purposes set forth.

2. In combination, the tracks A, the housings B, and the attached weight N, the housings adapted to advance and retreat, and the weight N having spring-pockets and supporting-rod openings, the supporting-rods K and L, with flanged chain-rod T, the springs J and chains E, with flanged spring-rods O connected to them, and the chain-rods F, with the chambers I and the springs J, substantially as and for the purposes set forth.

3. In combination, the tracks A, the housings B, and the attached weight N, the housings adapted to advance and retreat, and the weight N having supporting-rod openings, the supporting-rods K and L, and the springs J and chains E, the chain-rods F, with the chambers T and springs J, and the gage-beam H and the anchoring-bar G, adapted to hold the 90 spring-chambers in position, substantially as and for the purposes set forth.

4. In combination, the tracks A, the housings B, having spring-pockets carrying springs J, the under friction-bar, D, adapted to bear against the pocketed springs and having hooks D', the attached chains E, with weight N, the latter having supporting-rod openings, the supporting-rods K and L, with the connecting-rod T, the chain-rods F, with the chambers I 100 and their springs, and the gage-beam H and the anchoring-bar G, adapted to hold the spring-chambers in place, substantially as and for the purposes set forth.

5. In combination, the tracks A, the housings B, and the attached weight N, said housings adapted to advance and retreat, and the weight N having spring-pockets and supporting-rod openings, the supporting-rods K and L, with connecting chain-rod T, the springs J, and the chains E, the gage-beam H, adapted to hold spring-chambers I and support the rods K and L, and the springs surrounding the supporting-rods K and L, substantially as and for the purposes set forth.

6. In combination, the tracks A, the housings B, and the attached weight N, having spring-pockets and supporting-rod openings, the supporting-rods K and L, with connecting chain-rod T, the springs J, and the chain E, the gage-beam H, adapted to hold the supporting-rods and the springs surrounding them, and the plate S, interposed between said springs and the weight, substantially as and for the purposes set forth.

7. The combination of the housings B, adapted to advance and retreat, the connected chains E, and weight N, having attached shackles P, for lifting the same, the weight-supporting rods K and L, and the coupling-bar R, made in halves, with surrounding parts allowing the supporting-rods to pass, substantially as and for the purposes set forth.

8. In combination, the rails A and the hous-

ings B, adapted to advance and retreat, the springs J, and the adjustable fender-plates B', supported by said housings, the gage-beam H, adapted to support springs to receive the bearing-bar A', said bearing-bar A', and the bed-bars C, with upper friction-bar, Z, and lower friction-bar, D, substantially as and for the purposes set forth.

9. In combination, the rails A and the housings B, the gibbs U, fastened to the ends of the housings and locked thereto by their upturned ends, and adapted to receive the weight of the train and keep the ends of the housings in place, the friction-bar D, and the bed-bars C, with the springs J, and fender-plates B', adapted to move back and forth with their springs, substantially as and for the purposes set forth.

10. In combination, the rails A, the housings with a projecting end and with an upper and lower face, having pockets cast therein adapted to contain springs, the said springs J, and the fender-plates B', adapted to move back and forth with said springs, and the gibbs U, having lugs U' attached thereto and serving as a medium by which the device is operated.

11. In combination, the rails A, the housings B, situated thereon, with an upper and lower vertical face with spring-pockets therein, the springs J, adapted to fit within said pockets and having a fender-plate, B', adapted to move back and forth with said springs, and a rod, a, suited to hold the parts in position, substantially as and for the purposes set forth.

12. In combination, the rails A, the housings B, situated thereon and adapted to advance and retreat, and having vertical faces with spring-pockets cast therein adapted to contain springs, the said springs J, and the fender-plates B', adapted to move back and forth with said springs, and having a rod, a, to hold the parts in place, the gage-beam H, with spring-pockets cast therein, and the gage-beam springs J, adapted to receive the abutment of the housings, substantially as and for the purposes set forth.

13. In combination, the rails A, the housings B, adapted to slide thereon, and having vertical faces with pockets therein adapted to hold

springs, the springs J, adapted to be held within said pockets and having fender-plates B', suited to move back and forth with said springs, and having a rod, a, to hold the parts in position, the attached weight N, with spring-pockets, and its springs J, and the tubular supporting-rod K and L, carrying spring-chambers and their springs, with a cross chain-rod and chains, substantially as and for the purposes set forth.

14. In combination, the rails A, the housings B, situated thereon and adapted to advance and retreat, the attached chains E, with weight N, the spring-pockets I, having slots for chain-rods F to work back and forth, and with springs J and the chain-rods F, operating substantially as and for the purposes set forth.

15. In combination, the rails A, the housings B, adapted to advance and retreat, and having springs J and adjustable plates B', with rods a, to hold the parts in place, a cross-bar, D, having an independent back-and-forth movement when the housings are at rest, and the springs J, to receive the bearing of said cross-bar in its movements, substantially as and for the purposes set forth.

16. In combination, the rails A, the housings B, adapted to advance and retreat, and having springs J and adjustable plates B', with rods a, to hold the parts in place, a cross-bar, D, having an independent back-and-forth movement when the housings are at rest, and the springs J, to receive the bearing of said cross-bar in its movements, and the gage-beam H, with its springs J, operated substantially as and for the purposes set forth.

17. In combination, the housings B, adapted to advance and retreat, and having abutting faces adapted to carry springs J and fender-plates B', said springs and fender-plates and the gage-beam H, with its springs J and the bearing-bar A' interposed between the housings and the gage-beam springs, and adapted to receive the bearing of said housings and work back and forth, substantially as and for the purposes set forth.
